TELEGRAPH SYSTEM

Louis M. Potts, Evanston, Ill., assignor to Teletype Corporation, Chicago, Ill., a corporation of Delaware

Original application October 20, 1941, Serial No. 415,694. Divided and this application June 30, 1943, Serial No. 492,913

16 Claims. (Cl. 178—53.1)

This invention relates to telegraph systems and more particularly to start-stop telegraph systems.

This application is a division of application Serial No. 415,694, filed October 20, 1941.

Systems comprising telegraph codes having uniform numbers of unit impulses are widely employed for the control and operation of various telegraph apparatus such as printers, keyboard mechanisms, and the like. One such code system which is often employed is known as the Baudot five-unit code and affords thirty-two basic permutative possibilities. It is often necessary that the selective requirements exceed the thirty-two basic selective possibilities afforded in the five-unit code, and when such need occurs it is possible to increase the number of selective possibilities by adding shift and unshift code signals. In this way it is possible, despite the fact that the available basic signaling possibilities are now reduced to thirty in number, to increase the total number of signaling possibilities, including said shift and unshift signals, to sixty-four.

It sometimes is desirable to have more than two shift code characteristics. It is possible to add extra shift and unshift code signals, but when this is done the number of signaling possibilities are reduced in number in the original code. Thus, it is desirable to be able to cause a shift or unshift condition to occur while retaining the thirty-two basic permutative possibilities.

Accordingly, the object of this invention is to enlarge the range of selective possibilities in start-stop telegraph systems without increasing the number of component impulses from that of conventional signals.

The systems as described hereinafter are illustrated in conjunction with a type wheel printer wherein it is possible to control selectively the shifting of a type wheel to any one of four desired positions. In general, the system which comprises the present invention is a system of responsive relay elements made to condition a receiver release magnet so as to be alternatively actuatable to impulses of two different electrical characteristics, but in each case to such a characteristic as is opposed to that of the final impulse of a preceding signal. In this way the nature of the final impulse of a signal may be varied and thereby enter into the code combination of its associated signal as a permutation impulse. Also, as this impulse serves as a stop impulse no matter what its electrical nature happens to be, the need for a separate stop impulse is obviated. The systems disclosed herein-after are described as being responsive to a per-

forated tape, but obviously, any suitable signal originating means could be used.

For a more comprehensive understanding of the present invention reference may be had to the accompanying drawings and to the detailed specification following hereinafter in which similar reference characters indicate corresponding parts throughout, and in which:

Fig. 1 is a schematic diagram of a system illustrating the invention, which utilizes positive, negative, and no-current for signal composition with the marking impulses therein varying between positive and negative current characteristics for the purpose of obtaining a shift control;

Fig. 2 is a fragmentary plan section of a modification of the invention;

Fig. 3 is a diagrammatic view of the selector mechanism shown in Fig. 2 as connected with the mechanism for altering the position of the type wheel;

Fig. 4 is a schematic diagram of a system which uses an apparatus of the type shown in Fig. 2, in which the signals are of conventional length but in which a sixth impulse is incorporated with a stop interval and the start impulse is varied to contrast with the stop impulse; and

Fig. 5 is a diagrammatic chart of a code signal such as may be used in the system disclosed in Figs. 2, 3, and 4 showing how its component parts are functionally allocated.

It is believed that a brief and general discussion of the control means for selecting the type wheel position is all that is necessary in the present disclosure, as this has been fully explained and illustrated in the previously mentioned copending application of which this is a division.

Referring to Fig. 1, a type wheel designated generally by the numeral 11 is shown as having four annular rows of type pallets 12 thereon. The type wheel 11 is secured upon a rotatable shaft 13, so that the proper type pallet which has been selected will be advanced to a position adjacent a printing platen (not shown) against which the selected character is operated to effect printing. The desired row of type pallets is presented before the platen by means of a change in vertical position of the type wheel 11. This is accomplished by giving vertical movement to the type wheel 11 by means of a bracket 14, which embraces the shaft 13 below a supporting collar 16. Vertical movement of the bracket 14 is possible, according to the position of members 17 and 18 with respect to shoulders 19 and 21 which form a part of a recess 22 within the

bracket. The various positions of the two members and the resulting position of the type wheel 11 is clearly explained in the above-mentioned copending application.

For the present it is sufficient to say that the member 11 is under the selective control of shift and unshift code signals which, through the start-stop selecting mechanism of the printer, position member 11. A more complete description of this operation may be had by referring to the previously mentioned copending application, Serial No. 415,694, of which the present application is a division. The position of member 18 is determined mechanically by means of the system which incorporates the present invention. The mechanical means which causes the bracket 14 to be moved in a vertical direction is clearly explained in the afore-mentioned copending application of which this is a division.

Preferred system

Fig. 1 illustrates a signal transmission system for effecting the control of a double character shift supervision (a total of four shift positions). This system contemplates the use of a five-unit line signal code, the secondary shift signal characteristic being inherent in the nature of the polarity of marking impulses. It is proposed, accordingly, to make available for signal transmission both positive and negative current potential, either one of which is to be used permutatively with no-current to produce five-unit Baudot permutation code signals, but whether the marking signals are constituted of positive current or of negative current will determine the alternative characteristic of the secondary shift control.

In the diagrammatic representation, Fig. 1, the reference character 30 denotes a transmitting distributor of the rotary type which may be controlled by start-stop or multiplex (synchronous) supervision. A tape sensing unit generally indicated 31, is provided with six tape hole feelers. Five of them are committed to the five-unit signal code, and their contactors 32 are therefore associated with the five segments of the transmitting distributor 30, but a sixth one whose contactor is indicated 33, is designed to sense the presence or absence of a sixth perforation in a six-hole tape, and serves to introduce positive or negative current to the contact segment 34 which, in turn, introduces corresponding current condition to the marking signals, as will now be described.

The tape transmitting apparatus 31 may be of any conventional type, one embodiment being illustrated in U. S. Patent No. 1,661,012, except that instead of providing but five sensing levers and associated electrical contacting apparatus, unit 31 may correspond in all respects thereto so far as the conventional feelers levers 32 are concerned, special feeler 33 being simply an additional member and having an additional pair of contacts with separate contacting points represented by the rectangles 36 and 37. The cable 38 contains five lines, each connecting one of the feeler lever contactors 32 with its associated segment in distributor ring 39. A conductor 41 connects special feeler contactor 33 with one terminal of the winding of a polar relay 42. Continuing from the other terminal of polar relay 42 is a conductor 43 leading to the special segment 34 of a distributor ring 44 adapted to be bridged by a pair of brushes 46 with the grounded ring 47.

It is to be noted that the afore-mentioned segment 34 aligns with and corresponds to the distributor cyclic period coincident with the conventional start segment 48 of distributor ring 39 and that this cyclic interval is in advance of the first one of the five permutation code segments of ring 39. For this reason, it will be observed, the operation of relay 42 will occur in advance of the time that brushes 46 encounter said permutation code segments of ring 39. Thus, the transfer operation on the part of relay 42 is made to occur during a no-current interval of the conductor 51 (segment 48 having no connection with any of the feelers) and there is in this way prevented the possibility of foreshortened or clipped impulses, a result which might not be avoided save through the utilization of a neutral interval during which to exercise the current reversal.

The normal position of the tape feelers and their associated contacts 32 and 33 may be supposed in the manner illustrated in Fig. 1; that is, with their contacts engaging terminal blocks 52 and 36. Accordingly, when presented against the surface of the tape, said contacts 32 and 33 seek to engage the contact blocks 53 and 37, those encountering perforations being permitted to do so and accordingly connecting their respective segments of ring 39 with block 53 which, in turn, receives current potential over a conductor 54, contactor 56, from one or the other of a pair of opposite current sources 57 and 58. Those not encountering such perforations, however, will, during the critical portion of the signal transfer, fail to obtain current inasmuch as they will remain in engagement with the terminal block 52 and hence cause to be conditioned their respective segments of ring 39 without electrical potential or with "no-current".

Relay 42 being of the polar type, its armature 56 will move to the right or to the left engaging the contact points 57 or 58 in accordance with the nature of current coming over conductor 41 from contactor 33 which may engage positive current block 37 or negative current block 36. When placed in either of its positions, armature 56 remains there until altered by an opposite polarity introduced into the windings of its relays 42. Accordingly, it will be understood that the presence or absence of a sixth perforation will correspondingly impress block 53 with positive or negative current and that on this account, permutation code signals generated over the segments of ring 39 may be either positive and no-current or negative and no-current and that they will accordingly be so issued out over line conductor 51.

At the receiving station, there is connected to line conductor 51, in series, the selector magnet 59 and a receiving polar relay 61 whose armature 62 will engage or withdraw from its contact point 63, depending upon whether the marking impulses of the received signals are of positive or negative polarity. In accordance with the movements of armature 62, operating current will be introduced to or withheld from the winding of a secondary shift control magnet 64, over an obvious circuit, Fig. 1.

A bell crank armature 66 pivoted at 67 and responsive to the energization or nonenergization of magnet 64 actuates an intermediate bell crank lever 68. The bell crank lever 68 engages a projection 69 integral with the horizontally shiftable member 18. Thus, member 18 may be positioned

with respect to the shoulders 19 and 21, depending on the character to be printed.

Since the operation of secondary shift control magnet 64 by the current characteristics as afore-described need not be established except during any one impulse of a signal, and since the most favorable opportunity for executing the performance (energization or release) of said magnet 64 is coincident with the stop (R) impulse interval, means have been provided for shunting the supervisory polar relay 61 so that it may not fluctuate except during the precise interval coincident with the stop signal impulse. This supervision is exercised by a special cam carried upon a distributor shaft 71 which, acting through a follower lever 72, causes the contact pair 73 to come ajar during the distributive interval coincident with the stop impulse, thereby removing the shunt ground from a local circuit, cutting into circuit relay 61 together with selector magnet 59 and permitting both members to respond to the stop impulse. At all other times in the distributive cycle, however, the apex of said cam of the distributor shaft 71 is withdrawn from the follower lever permitting contact pair 73 to engage and to thereby effectively shunt relay 61 out of the signal responsive circuit.

It is to be understood, therefore, that the showing of Fig. 1 illustrates a manner of controlling the functioning of a secondary shift control structure under the supervision of a five-unit code. A shift characteristic for the purpose of supervising a secondary type wheel shift function has been embodied into the standard five-unit code by alternating the current characteristic of the marking impulses between plus and minus, the spacing impulses being in all cases no-current.

Modified system

In Figs. 2, 3, and 4, there is illustrated a second system of printer control and line transmission for utilizing the five-unit Baudot code signal in such a manner that it will afford six-unit signaling possibilities. Other manners of accomplishing this result have already been disclosed in connection with the embodiments described above, as by providing means for supplying two current conditions for the marking impulses.

In the manner of signaling contemplated in connection with the present embodiment, there is employed a five-unit Baudot type code combination signal having, in addition to the conventional five selective impulses, a special impulse utilized for supervising secondary shift control and a start impulse interval of a polarity opposite to that of its preceding or special impulse interval, under the specific contemplation of the five-unit code combination impulse interval.

In other words, whereas conventional five-unit permutation code signals being provided with seven componential impulse intervals contemplate start and stop impulses of predetermined and invariable line characteristics, means are herewith provided for varying the characteristic of the stop signal interval so that in accordance with the electrical nature it may have utility for determining case selection as well as for phasing supervision by making the start initiating apparatus responsive to a start impulse condition of electrical polarity opposite to that of the immediately preceding stop impulse interval which, as has been said, may consist of either one of two alternative line conditions.

In the incorporation of this plan of operation, it has been found expedient to utilize positive and

negative current conditions to represent marking and spacing instead of the conventional practice of utilizing current and no-current conditions for this purpose. Referring to Fig. 4 it will be seen that there will be utilized for the purpose of signal translation a six-feeler sensing apparatus generally indicated by the reference character 81. Sensing mechanism 81 is illustrated as having seven contactors 82 to 88, inclusive; however, contactors 87 and 88 both are carried upon a single feeler lever while each of the remaining contactors 82 to 86, inclusive, is carried individually upon a feeler lever.

In accordance with the operation of its feeler lever, each contactor is spring urged so that it will engage the contact block towards the right and is capable of movement in an opposite direction so as to engage the contact block towards the left, as illustrated in Fig. 4. The contact block at the right is comprised of a large section indicated 89 and a smaller section insulated therefrom indicated 91. The contact block at the left is similarly comprised of two sections, the larger one indicated 92 and the smaller one 93. Moreover, as may be noted the small contact block 93 is connected electrically over an obvious conductor with the large contact block 89 and correspondingly small contact block 91 is connected electrically with the large contact block 92. Opposite sources of grounded potential indicated 94 and 96 are connected respectively to the contact blocks 93 and 91 and over conductors 97 and 98 to the oppositely placed contact points of armature 99 under the control of a polar relay 100.

The winding of said relay 100 is connected at one end to the afore-described feeler contactor 88 and at its other end to a distributor segment 102 situated in distributor ring 103. This distributor 104 which includes also distributor rings 106, 107, and 108 is of the start-stop type having a brush carrier 109 which supports two pairs of bridging wipers 111 and 112. Brush carrier 109 of transmitting distributor 104 is conventionally illustrated in Fig. 4, but it is to be understood that this element is driven through a friction coupling preferably in a rotary direction and that it may be restrained from movement by the intervention of an armature 113 under the supervision of start magnet 114. Also, that the pair of wipers 111 serve to connect segmented distributor ring 106 with the solid distributor ring 107 which is electrically connected to line conductor 116, and that the pair of wipers 112 correspondingly connect distributor ring 103 which contains the segment 102 afore-described with the grounded distributor ring 108.

Attention will now be given to distributor ring 106 which, as may be observed in Fig. 4, is made up of seven segments. When the brush carrier 109 is in its arrested position, wiper 111 is contacting the slightly longer segment designated 5 in the distributor ring 106. Also, it may be observed that following the segment 5 which serves also in the capacity of a stop segment as will later be described, there is encountered a start segment designated by the character S.

Following this segment is one designated 0 (zero), which has been arbitrarily assigned to the function of supervising the secondary shift. This control is otherwise executed, in accordance with the present embodiment, in a manner generally similar to that described above in connection with the preferred embodiment.

The remaining segments 1, 2, 3, etc., including segment 5, which as has already been stated,

functions in a dual capacity, serve to distribute those signal impulses which relate to the composition of the permutation code. Segment 5 is connected over a conductor 117 to the feeler 87. Segment S is connected over a conductor 118 to the armature 99 of polar relay 100. Fig. 4 illustrates diagrammatically transmitting station equipment including a perforated tape controlled mechanism and a rotary signal transmitter under the supervision thereof for issuing signals of a type adapted to exercise the control function including primary and secondary shift supervision for printing apparatus having mechanically the characteristics exemplified in the showing of Figs. 2 and 3.

As the brush carrier 109 proceeds in the downward direction as indicated by the arrow 119, the pair of wipers 111 leave segment No. 5 and encounter segment S bridging this element of distributor ring 106 with the solid line ring 107. Assuming, for the sake of illustration, that the perforated tape signal which has just been positioned and which has been impressed upon the feeler levers of record reader 81 is such that contactors 87 and 88 (which operate in unison) are moved to the right, that is to say, with contactor 87 engaging block 89 and contactor 88 engaging block 91, distributor segment No. 5 will have received positive current potential from grounded battery 94 over conductor 117. This circuit is traceable from positive battery 94, segment 93 to segment 89, feeler 87, conductor 117, segment No. 5 of distributor ring 106, brushes 111 to outgoing line ring 107 which is grounded at the receiving station. As the brushes proceed to the next segment which is designated S, opposite polarity is issued from grounded battery 96 if polar relay 100, in accordance with its preceding operation, has been left in a position whereat its armature 99 engaged the contactor of conductor 98. This circuit is traceable from negative battery 96, conductor 98, armature 99, conductor 118, segment S of distributor ring 106, brushes 111 to line ring 107.

If instead of the supposed example described above, the particular signal had been one in which the feeler lever with which contactors 87 and 88 are integrally associated was positioned to the left causing engagement with contact block 92 and 93 instead of contact block 89 and 91, the electrical characteristics relative to segments 5 and S would be opposite to that just described. With the brushes 111 passing over segment 5 negative potential would be supplied from grounded battery 96, segment 91, segment 92, feeler 87, over conductor 117 to segment No. 5. Likewise, positive current would be supplied from grounded battery 94, conductor 97, armature 99 of polar relay 100, which has been energized to its opposite position, conductor 118 to segment S of distributor ring 106. Each of the feeler contactors 82 to 86, inclusive, is connected over an individual conductor with an associated segment 0 (zero) to 4 of the transmitting distributor ring 106. Accordingly, when a feeler lever encounters a perforated position in the tape, its contactor will be moved into one position, say the right-hand one, engaging the contact block 89 while if its said feeler lever encounters a nonperforated position its contactor will assume an opposite condition; that is, contacting the opposite block 92. The designation of positive or negative signals to correspond with perforated or nonperforated signal components is arbitrary, and it is

to be understood that the reverse association is equally feasible.

The foregoing is true not only of the conventional five feeler levers of contactors 82 to 86, inclusive, but also of the special feeler lever with which are associated two contactors 87 and 88, as has already been mentioned. One significant difference, however, does prevail which will now be noted. In the case of the special or sixth feeler lever, when a perforation is encountered and, say both contactors are moved to the right, contactor 88 will be introducing negative current from battery source 96 to the winding of bias polar relay 100 while contactor 87 will be introducing positive battery from source 94 over conductor 117 to the stop segment 5. Conversely, with the contactors 87 and 88 in the opposite position, that is, engaging contact blocks 92 and 93, positive current originating from source 94 will be introduced through feeler 88 to the winding of bias polar relay 100, while negative current originating from source 96 will be introduced over conductor 117 to stop segment 5. Accordingly, since armature 99 of relay 100 is connected to the start segment S, the result of the operation of the sixth or special feeler lever will be understood as one controlling the reversal of potential for start segment S, that is to say, with a given condition on the part of segment 5 which may be either positive or negative the sixth feeler lever controlling contactors 87 and 88 operate to provide an opposite current potential to the start segment S.

The purpose in having provided polar relay 100 with its armature 99 connecting positive or negative current to the segment S instead of directly connecting the contactor 88 to said segment S is one of permitting the start impulse signal interval to be stored. The transmitter 40 utilized is of the well-known magnet type wherein a new signal is sensed during the start interval. If a new signal should be sensed which would cause the feelers 87 and 88 to move to their opposite position the start impulse would 45 be of the same polarity as the stop impulse. However, by providing the polar relay 100, the armature 99 will be held in a position whereby potential opposite to that of the stop segment 5 will be assured, as the armature 99 retains such 50 position until the brushes 111 have passed the start segment S, or until brushes 112 sweep across segment 102 of ring 103, thus providing a grounded circuit for the polar relay 100. At this 55 time the armature 99 may move to the opposite side if the feelers 87 and 88 have moved, but the start impulse has already been transmitted.

In Fig. 4, the reference character 121 designates a receiving station and within said outline are contained the symbols representing vital apparatus responsive to the signals generated by the transmitting distributor 104. Of these, the reference character 122 denotes a bias polar relay whose armature 123 is grounded, and is adapted to reciprocate between two contact points 124 and 125 which are part of a local circuit for supervising the operation of principal control magnets 127, see also Fig. 2.

Also situated in said receiving station local circuit are a pair of contactors indicated 128 and 129. The former reciprocates between a pair of contact points 131 and 132 and the latter between a pair of contact points 133 and 134. In the printer apparatus which is shown in mechanical detail in Fig. 2, contactor 128 and its associated contact points 131 and 132 are indicated as an

assembly controlled by a follower arm 136 pivoted at 137 and supervised by a cam apex 138 which is one of an assembly carried upon a distributor cam shaft 139. The shaft 139 may be driven by any well-known means (not shown).

Also carried on shaft 139 as an integral part of the afore-mentioned cam assembly and in addition to the afore-described cam having the apex 138 are five selector signal cams whose apices 10 actuate the five bell crank levers 141 mounted in pivotal alignment upon shaft 137 and hence affording visibility only to the foremost ones in Fig. 2.

A sixth cam similar to said five distributor cams is utilized for the purpose of controlling a storage lever 142, also shown in Fig. 3, which actuates a bell crank 143 for the purpose of obtaining the referred to secondary shift control. In addition to the cams already designated in the assembly carried by shaft 139 is one indicated 144 having a plurality of spaced apices, which when said cam assembly is rotating, serve to rock an armature bell crank 146 about its pivot 147 for the purpose of presenting its magnetically attractive arm 148 against the pole face of magnet 127. This operation of cam 144 in assisting the armature 146 and thereby diminishing the work of magnet 127 is in accordance with recognized practice in printing telegraphy.

As illustrated in Fig. 2, storage lever 142 is disposed below the other storage levers 149 and 151. This arrangement is in a general sense arbitrary, since the shift signal impulse, in the particular instance corresponding to the segment 0 on the distributor ring 106, Fig. 4, may be located if preferred in any other position with respect to the componential sequence both in distributor ring 106 as well as in the stack of selector storage levers, Fig. 2, designated 142, 149, and 151. Storage levers 151 are five in number corresponding to the signal components which utilize the segments 1, 2, 3, 4, and 5 in the transmitting distributor ring 106. Storage lever 149, together with the top one of levers 151, correspond to the code signal impulse occupied by the segment 5, and in the order designated each impulse ultimately serves to place its associated lever 149 or 151 in one or another of its two possible positions, against pin 152 or pin 153.

For the purpose of understanding the principles of the instant improvement, it will suffice to state that ultimately the storage signal is manifest by a conditioning of the several storage levers 142, 149, and 151 with the lever 142 exercising the function of controlling secondary case shift bell crank 143 and levers 151 functioning to condition the setting of code discs 154 which are five in number.

Storage lever 149 controls the shifting of above-mentioned contactor 129. Accordingly, when it is found in the position as illustrated in Fig. 2, it permits contactor 129 to engage its upper contact 133, and when it is in an opposite condition such as that occupied by the counterclockwise extreme storage lever 151, in Fig. 2, said lever 149 by its protuberance 156 will engage the insulated extremity of contactor 129 and thrust the latter member so that it will disengage contact 133 and engage contact 134 instead.

A supervision of contactor 128 is had by follower lever arm 136 under the control of cam apex 138, that is, when apex 138 is in the position indicated, contactor 128 is thrust against its left contact 131 but at all other times, that is, when apex 138 is clear of the follower arm 136, contactor 128 is permitted through its own spring 70 75

tension to recede from contact point 131 and to engage instead contact point 132. There will now be described the effect of the supervision of contactors 128 and 129 by the above-described apparatus.

Let it be assumed for the sake of illustration that a particular code signal transmitted over distributor 104 is comprised of a certain combination of code impulses whose fifth component (there being a total of six components including 0) is constituted of marking characteristics, that is, the current characteristic which will position its sword 162 in the manner opposite to that indicated in Fig. 2 so as to place storage lever 149 in the position opposite to that indicated in this illustration. Accordingly, contactor 129 will be permitted to recede from contact point 133 (assuming that a preceding signal differed in respect to this signal component) and to engage instead its contact 134. This will correspond also to the placement of contactor 128, as illustrated in Fig. 4. In order to produce this result, the nature of the signal impulse will be such as to affect the polar relay 122 to cause it to move its armature 123 to engage contact point 126 so as to close the circuit for selector magnet 127 and to cause the armature lever 158, Fig. 2, to assume its marking position. Subsequently, there will follow the start signal impulse whose effect upon relay 122 will be opposite to that just described in connection with the No. 5 signal impulse, which reversal is assured by the apparatus of the transmitting distributor described above. In consequence, relay armature 123 will be moved clockwise to engage its contact point 124, opening the circuit for energizing selector magnet 127 and thereby releasing the selector apparatus for a given cycle.

Under the alternative condition of operation, that is, with the No. 5 impulse being of spacing nature, contactor 129 will be withdrawn from contact point 134 and thrust into engagement with contact point 133 instead. Cam shaft 139 carries in addition to the afore-described operating cams 138 and 144, a spiral distribution of cam apices indicated 159, five in number. Each one of these is related to one of the signal impulses 1 to 5, inclusive, whose corresponding segments appear in the distributor ring 106, Fig. 4, while the final one of said series designated 161, Fig. 2, is, in accordance with the present embodiment, of double width.

This is so because unlike the other of the cams 159 which serve to actuate but a single one of the claw levers 141, it alone actuates a pair of said claw levers 141; namely, the claw lever which actuates the sword 157 identified with the No. 5 impulse interval and the sword 162 which controls contactor 129. This is so because said sword 157 controls its associated code disc and sword 162 must substantially concurrently condition contactor 129 through the lever 149. Since said levers 141 are all of the same contour, they may not be differentiated in the showing of Fig. 2, however, on account of the spiral arrangement of said cams 159, each claw lever 141 will be operated at a particular cyclic interval, except said two claw levers 141 which are operated in unison by the special apex 161. Each claw lever is provided with a sword 157 but the sword which is associated with the anterior lever 141, as viewed in Fig. 2, has been specially designated 162. Each sword 157 and 162 terminates with a blunt point projection which rests against one side or the other of a hump 163 of an intermediate lever element, five of which are designated 151 but the

one related to the sword 162 of which is designated 149. The five similar levers 151 each are provided with a tail piece 164 that serves as a locking projection by being placed on one side or the other of a locking bail 166, which member assumes the position indicated in Fig. 2, except during a brief interval following the conclusion of a particular signal when its lever arm 167 is released by the operation of an auxiliary shaft, not shown.

Accordingly, while the several swords 157 and 162 may assume one position or the other as its abutment 168 or 169 encounters the downwardly extending vane 171 or 172 of armature lever 158, levers 149 and 151 may not be correspondingly positioned until said swords 157 and 162 are thrust downwardly by the clockwise movement of the claw levers 141, which movement is urged by their individual springs 173 as well as by auxiliary individual springs carried upon an integral extension of lever arm 167.

The auxiliary springs of lever arm 141 are not shown in Fig. 2 of the accompanying drawings, but reference may be had to the afore-described copending application where it is explained that their function is of an auxiliary nature and to assist the principal actuating springs 173. None of the springs 173 or the auxiliary springs mentioned may actuate their associated claw levers 141 during the time that the locking bail 166 intervenes by blocking the extending portions 164 of levers 151. However, since lever 149 is not provided with an extension 164 as are the remaining ones of the levers designated 151, its response to its associated sword 162 will occur immediately following the instant when cam apex 161 passes the follower projection of claw lever 141 which carries said sword 162.

Thus, while the consummation of a signal transfer relating to a particular set of code impulses of any signal must await a brief interval following the fifth or stop code impulse, the actuation of contactor 129 by the projection 156 of special storage lever 149 follows immediately upon receipt of the fifth code impulse. This assures the operation of selector magnet 127 for the purpose of arresting the rotation of shaft 139 coincidentally with the signal interval corresponding to the stop or fifth code combination impulse, even though the other purpose of the particular impulse, namely, that of setting one of the code discs 154, may await its regular period of operation which, as has been said, occurs after the lapse of a brief time interval and, in fact, during the occurrence of a succeeding code combination signal.

Cam apex 138 is specially provided for the purpose of actuating the afore-described arm 136 which, in turn, controls contactor 128. Cam apex 138 is effective to thrust contactor 128 against its contact point 131 for a period commensurate approximately with the beginning of the stop or No. 5 code combination impulse and continuing through the start impulse S and to the 0 (zero) or shift controlling impulse. At other times, contactor 128, see also Fig. 4, engages its contact point 132 for a purpose which will now be described.

Operation of the modified system

Concise stated, armature 123 of relay 122 fluctuates in accordance with each signal impulse, contactor 128 being controlled by cam apex 138 resting against contact point 132 at all times except

during the stop and start signal interval, and contactor 129 being controlled by the No. 5 or stop signal is moved into one or the other of two alternative positions as a result of the operation of the transfer mechanism, described above, only during the period corresponding to this impulse. Under an assumed set of conditions, in response to marking signals, both armature 123 and contactor 129 will be deflected downwardly, that is, to engage their contact points 126 and 134, while under spacing signal impulses, said armature and contactor will be in their opposite position, that is, engaging respectively their contact points 124 and 133. Also, it is to be recalled that since the No. 5 impulse functions in a dual capacity of effecting the distributor stop control as well as of entering into the permutation code, each cycle must be considered as including a part of the preceding No. 5 impulse, which affects the current characteristic of the start impulse as well as of the concluding No. 5 impulse, because it, together with the impulses No. 1, 2, 3, and 4, comprises the code combination of the particular signal.

Accordingly, when the No. 5 impulse of a preceding signal happens to be marking, armature 123 will be thrust into engagement with its contact point 126, contactor 128 will be thrust into engagement with its contact point 131 (on account of the operation of cam 138), and contactor 129, as a result of the transfer operation, will be moved into engagement with its contact point 134. This will complete a circuit traceable from grounded battery at 176, winding of magnet 127, conductor 177, contactor 129, and its contact point 134 with which it is then in engagement, conductor 178, contact point 126, and its armature 123 which is then in engagement with it, to ground. As a result of the continued energization of magnet 127, its armature is held and the rotation of shaft 139 is arrested in accordance with the conventional operation of printing telegraph selector shafts. This condition continues until the circuit for energizing magnet 127 is broken, which change occurs upon the receipt of a proper start impulse over segment S of transmitting distributor ring 106. The polarity of the start signal being opposite to that of the No. 5 or stop signal impulse, as already explained, causes armature 123 to be moved to engage its contact point 124 and away from its contact point 126. This interrupts or opens the circuit for magnet 127, causing the release of its armature 128 and consequently initiating the rotation of receiving distributor shaft 139 in a manner clearly described in the copending application referred to.

As distributor shaft 139 rotates, cam apex 138 rides off the projection of arm 136 permitting contactor 128 to be drawn away from its contact point 131 and to come into engagement instead with its contact point 132, meanwhile contactor 129 remaining in engagement with its contact point 134 because it can be changed only during the occurrence of the fifth impulse. As a result of the change in contactor 128 from contact point 131 to contact point 132, no effect is obtained at this time, magnet 127 continuing to be de-energized until during the course of the succeeding six signal impulses, 0, 1, 2, 3, etc., armature 123 in response to its relay 122 returns to engage its contact point 126, which response can occur only under the control of marking signal impulses.

In the event that a marking impulse is received during the 0 (zero) impulse interval, the action of one of the swords 157 upon the storage lever

142 will cause bell crank 143 to be rotated clockwise, in a manner and for a purpose to be described later. In the event marking impulses are received for any of the other impulse intervals 1 to 5, inclusive, their storage levers 149 and 151 will be accordingly positioned, causing corresponding placement of the several code selector discs 154 after the selection has been completed and the transfer mechanism operated, but of particular significance in this connection will be the current characteristic of the No. 5 signal impulse.

If this signal impulse is again marking in nature, the succeeding operation will be the same as the one just described except for the variations which may occur in the code combination, but if instead the signal impulse corresponding to the No. 5 interval happens to be of spacing nature, then armature 123 will respond by engaging its upper contact point 124 and sword 162 will be disposed in the manner illustrated in Fig. 2. As a result of the latter incident, contactor 129 will be permitted to engage its upper contact point 133 instead of the lower contact point 134, while on account of cam apex 138, contactor 128 will again be thrust against contact point 131. Thus, a circuit will be completed for energizing the magnet 127 traceable from grounded battery 176, through the winding of magnet 127, conductor 177, contactor 129 which is then in engagement with its contact point 133, conductor 179, contactor 128 and its contact point 131, conductor 181, contact point 124 and armature 123 which is then in engagement with it, to ground.

As a result, magnet 127 is held energized which is the proper condition corresponding to a stop impulse until an opposite current condition is received by relay 122 causing its armature 123 to be withdrawn from contact point 124 and to engage instead contact point 126. When this occurs, contactor 128 is still held in engagement with its contact point 131 because of the described function of cam 138, which maintains said condition until after the interval corresponding to the start, S, impulse. Meanwhile, the last described movement of armature 123 causes the energizing circuit for magnet 127 to be broken and accordingly releasing its armature 148 for the purpose of initiating rotation of receiving distributor shaft 139, as afore-described.

Thereafter and coincident with the 0 (zero) signal interval, apex of cam 138 restores contactor 128 to its condition prevalent during the major portion of the cycle; that is, engaging its contact point 132. When this occurs, that is, when armature 123 of relay 122 engages contact point 126, marking impulses are thereafter interpreted as magnet 127 energizing impulses, because contactor 129 continues in engagement with its contact point 133, causing the magnet 127 energizing circuit to be completed over the following described course. The current originates with grounded battery 176 through the winding of magnet 127, conductor 177, contactor 129, and its contact point 133, conductor 179, contactor 128 and its contact point 132, conductor 178, contact 126 and armature 123, to ground. Thus, phasing of the receiving magnet 127 as well as of its controlled shaft 139 is regulated notwithstanding the reversed condition of the No. 5 and start impulses.

Referring now to Fig. 3, it is to be seen that the apparatus as shown in this figure is very similar to the apparatus shown in Fig. 1, the difference residing in the manner in which one

of the members which controls the vertical movement of the type wheel is positioned. It is believed that a description of the operation may be given in which numerals similar to those used in the description of Fig. 1 are used, as far as is possible. When the sword 157 identified with the zero impulse interval is positioned in response to a spacing signal so as to engage storage lever 142 on the left side, that is, to the left of the pivot point of the lever, the lever 142 will be pivoted in a counterclockwise manner. Any counterclockwise movement of storage lever 142 causes an engagement and subsequent movement of bell crank lever 143 in a clockwise manner, about its pivot point. The end of bell crank arm 143 will engage the depending lug 186 of member 187, causing member 187 to move to the right, as viewed in Fig. 3. Any movement of the member 187 positions it and its lug 18 with respect to the shoulders, as previously described in the description of Fig. 1. Depending upon the position of lug 18 with respect to the shoulders 19 and 21, the type wheel 11 will be positioned vertically so as to present the line of type pallets 12 which it is desired to print against the adjacent platen (not shown). Member 187 is returned to its leftward position by means of a spring which is not shown in Fig. 3. This return occurs when the sword 157 is moved to the right of the pivot point of storage lever 142, as seen in Fig. 3. The pressure being removed from bell crank arm 143, the above-mentioned spring is strong enough to return member 187, overcoming any resistance which might be exerted by bell crank arm 143. It is not believed that a further discussion of the apparatus and its operation is necessary as such a discussion has been given with respect to Fig. 1.

While the foregoing electrical systems have been described as for a certain purpose and with the use of specific apparatus, it is to be understood that these systems could be used for other purposes and with apparatus other than that described. Accordingly, the invention is not intended to be restricted in any manner to the language of the detailed specification or to the illustration in the accompanying drawings, except as indicated in the hereunto appended claims.

50. What is claimed is:

1. In a start-stop recording apparatus, a selector magnet, means responsive to line signals comprised of a fixed number of permutation code impulses and a fixed number of phase regulating impulses, 55 each of said impulses being of alternative electrical characteristics for accordingly energizing or de-energizing said magnet, circuit conditioning means for rendering said magnet variably responsive to said code combination impulses, and additional means for preparing said magnet to respond invariably in accordance with said phase regulating impulses.

2. In combination, telegraph selecting apparatus, a receiving distributor having cyclic operation, means responsive to a pair of contrasting signal impulses and independent of their specific nature for regulating the phase of said receiving distributor, and means including a single selector magnet responsive to the electrical nature of a series of impulses at least one of said impulses being one of the phase impulses for controlling the selective operation of said apparatus.

3. In telegraph selecting apparatus, a selector mechanism, a single magnet for initiating said selector mechanism and for variably operating

it in accordance with line current variation, means responsive during certain current impulse intervals for energizing said magnet in response to marking current or for de-energizing said magnet in response to spacing current, and means effective during certain impulse intervals only for energizing said magnet in response to either kind of current and for de-energizing said magnet in response to succeeding opposite currents.

4. In a start-stop recording apparatus, a selector magnet, circuit means responsive to line signals comprised of a fixed number of permutation code impulses and phase regulating impulses each of alternative electrical characteristics, means for accordingly energizing or de-energizing said magnet, and circuit conditioning means for preparing said magnet to respond to said phase regulating impulses independent of their individual electrical character.

5. In a telegraph selecting apparatus, a selector mechanism, a single magnet for initiating said selector mechanism and for variably operating it in accordance with alternative line current variations, and means effective during certain impulse intervals for energizing said magnet in response to either of said alternative line current variations and for de-energizing said magnet in response to a succeeding opposite one of said variations.

6. In a start-stop telegraph system, transmitting apparatus comprising means for generating signals of a positive, negative, and no-current characteristic composed of a constant number of permutation code impulses and a constant number of phasing control impulses, receiving apparatus comprising a selector magnet responsive to all impulses of said generated signals, and a shift control magnet responsive to one impulse only of said generated signals.

7. In a start-stop telegraph system, transmitting apparatus comprising a six-unit permutation code senser, a transmitting distributor for issuing five-unit code signals comprised of a constant number of permutation code impulses of a positive, negative, or no-current characteristic, and a phasing control impulse of a positive or negative characteristic, the sixth code unit determining the electrical characteristics of said impulses, receiving apparatus responsive permutatively to the variations in the characteristic of said permutation code impulses to selectively record, and means associated with said receiving apparatus responsive to the variations in the characteristics of said phasing impulse for the purpose of obtaining a shift control.

8. In a telegraph system, means to transmit signals each composed of varying permutations of positive, negative, and no-current impulses, two magnets, means to operate one magnet according to the current or no-current nature of the impulses, means to operate the other magnet according to the positive or negative nature of the impulses, and means to make a record varying according to the operation of both magnets.

9. In a telegraph system, means to transmit signals each composed of the same predetermined number of positive, negative, and no-current impulses, two magnets, means to operate one magnet according to the current or no-current nature of the impulses, means to operate the other magnet according to the positive or negative nature of the impulses, means to make a

record varying according to the operation of both magnets, and means to start the receiver into operation under control of a particular one of the predetermined number of impulses.

10. In a telegraph system, means to transmit signals each composed of the same number of elemental intervals comprising positive, negative, and no-current impulses, two magnets, means to operate one magnet according to the current or no-current nature of the impulses, means to operate the other magnet according to the positive or negative of the impulses, and means to make a record varying according to the operation of both magnets.

15. 11. In a telegraph system, means to transmit signals composed of positive, negative, and no-current impulses, two magnets, means to operate one magnet permutably according to the current or no-current nature of the impulses, means to operate the other magnet according to the positive or negative nature of the impulses, and means to make a record varying according to the operation of both magnets.

12. In a telegraph system, means to transmit signals each composed of an invariable number of time intervals, two magnets, means to control one magnet during all the time intervals of said signal, and means to control the other magnet during a single one time interval of said signal.

13. In a telegraph system, means to transmit signals composed of positive, negative, and no-current impulses, two magnets, means to operate one magnet according to the current or no-current nature of the impulses, means to operate the second magnet according to the positive or negative nature of the impulses, a shunt circuit to prevent the operation of said second magnet except at a predetermined time, and means to make a record varying according to the operation of both magnets.

14. In a telegraph system, means to generate signals composed of current and no-current intervals, means to alter the polarity of successive signals during a no-current interval separating signals, and means to vary the record according to the polarity of the corresponding signal.

15. In a system of telegraph communication, the method of operation which comprises the steps of transmitting signals composed of a fixed number of time intervals, transmitting in said signals various permutations of current and no-current, varying the polarity of the current in different signals, and making a record in accordance to the permutations of current and no-current and also according to the polarity.

16. In a telegraph system, means to transmit groups of signals, each of said groups of signals comprising a plurality of impulses, at least one of said impulses assigned to a stop function, means to vary the character of said stop impulse according to the character to be transmitted, a recorder, a selector shaft in said recorder, a single selector magnet operated by all of said signal impulses, means to arrest said selector shaft under the control of said selector magnet at the end of each signal group independent of the polarity of said stop impulse, and means in said recorder to make a record under control of said selector magnet and varying according to the polarity of said stop impulse.
